UNITED STATES PATENT OFFICE.

JAMES B. SEAVERNS, OF CHICAGO, ILLINOIS.

DUMP GATE.

Original application filed June 5, 1922, Serial No. 566,004. Divided and this application filed May 14, 1925. Serial No. 30,151.

The present invention relates to dump gates.

More particularly the present invention relates to a construction of dump gates applicable to bins for containing stone, coal, sand, gravel, ashes, or the like. It is desired in practice to store large quantities of such weighty materials in bins and to open and close the bin gates for controlling the discharge by gravity of said weighty materials. In practice this weight often amounts to hundreds of pounds per square foot and a special gate construction is required to open and close said gates when they are under these heavy pressures.

The present application is a division of an application bearing Serial No. 566,004, filed by the present applicant on June 5, 1922.

An object of the present invention is to provide a gate construction in which a powerful leverage action may be obtained for operating same.

A further object is to provide dump gates which are sturdy in construction, efficient as closure members, and which may be readily operated in a controlled manner to allow the passage of dumpable material at the desired rate.

A further object is to provide dump gates suitable for heavy duty and adapted to cut off the flow of dumpable material when desired.

Further objects will appear hereinafter.

Referring to the drawings—

Figure 1 is a view in side elevation of a bin having applied thereto dump gates embodying the principles of the present invention;

Figure 2 is a sectional view taken along the plane marked by the line 2—2 of Figure 1;

Figure 3 is an end elevation of salient features of the construction shown in Figure 1;

Figure 4 illustrates a slightly modified construction; and

Figure 5 is a sectional view taken on the plane marked by the line 5—5 of Figure 4.

The numeral 10 indicates a bin supported on uprights 10'—10', said bin having the hopper 11. The lower extremity of the hopper may be provided with a chute 12 through which dumpable material may pass

downwardly from the bin 10. The bottom 55 of the chute 12 is provided with a pair of pivoted gates 13 and 14, which may be of the type commonly known as clam shell, said gates being capable of pivotal motion about the axes 15—15, which axes may lie in substantially parallel lines. When said gates 13 and 14 are moved into proximity to one another, they form a closure for the bottom of the chute 12, and when said gates are moved apart they provide between them 60 a space through which the dumpable material may pass, the gates 13 and 14 being movable approximately to the dotted line positions 13' and 14', respectively.

The gates 13 and 14 are adapted to be 70 moved in unison and have common control means. According to the construction shown in Figures 1, 2 and 3, said controlling means consists of a pair of operating arms 16 and 17 substantially symmetrically placed relative to said gates, of which the operating arm 16 has pivotal connection with the gate 13 and operating arm 17 has pivotal connection with gate 14. Operating arm 16 is connected to gate 13 at the point 16', while 75 operating arm 17 is connected to gate 14 at the point 17', said points 16' and 17' being located near to adjacent edges of gates 13 and 14. Said operating arms 16 and 17 also connect with the operating lever 80 18 which is pivoted about the vertical axis 19, said axis 19 being preferably located intermediate of the arms 16 and 17. The lever 18 may be mounted upon a bracket 20, which may be supported upon any convenient 85 structure, as, for instance, upon the uprights 10'—10', and is provided with a handle 21, by means of which a strong leverage action may be applied to the operating arms 16 and 17 for the purpose of operating the gates 13 and 14.

According to the structure illustrated in Figures 4 and 5, the gate 14 is provided with an operating arm 22 having pivotal connection therewith at the point 22', substantially 100 midway of the length of said gate, while the gate 13 is provided with the bifurcated operating arm 23 having the two bifurcations 24—24, which have pivotal connection with the gate 13 at the points 24'—24', located 105 at the opposite ends of said gate 13. Points 22' and 24'—24' should be located adjacent to the meeting edges of gates 13 and 14.

The arms 22 and 23 have a pivotal connection with the lever 25, which may be pivotally mounted on the bracket 26, the point 27 of pivotal connection of said lever 25 being placed intermediate of the connections between lever 25 and operating arms 22 and 23. The lever 25 may be provided with a handle 28 whereby said lever and consequently the arms 22 and 23 and gates 13 and 14 may be effectively operated.

By reason of the fact that the operating arms for the gates 13 and 14 are connected to said gates at points adjacent to their meeting edges, the forces are applied at the proper points to best overcome the resistance of the dumpable material. Due to the weight of said material, control of bottom doors is often difficult and distortion of such doors sometimes results. According to the construction of the present invention, however, a minimum of distortion is produced and the doors may be effectively controlled.

As will be noted from the drawings, and particularly Figures 1 and 4, the two opposite bottom edges of the chute 12 are curved and the dumping gates 13 and 14 have bottoms conforming to said curved lower edges. As indicated particularly in

Figure 1, the abutting edges of the gates 13 and 14 follow the bottom edges of the chute 12 in their opening and closing movements. By reason of this construction, the dumpable material is easily controllable so that the flow through said chute 12 may be controlled to a nicety.

Though certain embodiments of the present invention have been described in detail, many modifications will occur to those skilled in the art. It is intended to cover all such modifications that fall within the scope of the appended claim.

What is claimed is—

A hopper having side walls, a pair of pivotally mounted gates having cooperating edges, operating arms for said gates, one of said arms being pivotally connected to one of said gates at one side of said hopper, the other of said arms being connected to the other of said gates at the other side of said hopper, and a common operating lever for said arms, said operating lever being pivotally mounted between the points of attachment of said arms with said lever.

Signed at Chicago, Illinois, this 11th day of May, 1925.

JAMES B. SEAVERNS.
